HAND LOOM

Guy L. Phelps, Oklahoma City, Okla.

Application May 2, 1950, Serial No. 159,488

1 Claim. (Cl. 28—15)

1

This invention relates to a hand loom or weaving frame and it is one object of the invention to provide a loom consisting of a frame formed of a plurality of bars which are detachably secured to each other and form a frame of predetermined shape, the bars carrying upwardly projecting pins about which a strand of worsted or other suitable material is trained back and forth across the frame and another strand, or a continuation of the same strand, then interwoven with the first strand to form a woven mat which is then removed from the pins and may be used for any purpose desired or combined with additional mats to form a quilt, bed spread, or the like.

Another object of the invention is to provide a weaving frame consisting of bars which are firmly connected with each other but may be easily and quickly taken apart and the bars then placed in a small receptacle or tied together in a compact bunch until again needed.

Another object of the invention is to provide a weaving frame formed of bars which are detachably connected with each other by bolts passed diagonally through inner end portions of the bars and through selected ones of a plurality of openings spaced from each other longitudinally of the bars, thus allowing the bars to be so connected that a weaving frame of predetermined dimensions will be formed.

Another object of the invention is to provide a frame formed of bars detachably secured together, these bars having extensions consisting of auxiliary bars which are firmly secured to their companion bars and thus permit a frame which is appreciably larger than a frame formed by the first mentioned bars to be formed.

Another object of the invention is to provide a weaving frame which is simple in construction and may be manufactured at low cost.

The invention is illustrated in the accompanying drawings wherein:

Fig. 1 is a top plan view of the improved weaving frame or loom.

Fig. 2 is a sectional view taken transversely through the frame along the line 2—2 of Figure 1.

Fig. 3 is a fragmentary view showing a portion of a frame of modified construction partially in top plan and partially in section.

This weaving frame or hand loom consists of a plurality of bars 1 which have been shown as six in number but may be more or less according to whether the frame is to be of hexagonal shape, as shown, or some other shape. The flat inner end of each of the bars 1 is cut diagonally

2

and this flat inner end 2 of the bar is disposed in abutting engagement with the flat inner side face of the bar to which it is secured. Openings 3 are formed diagonally through the inner ends of the bars to receive securing bolts 4 and these bolts are each passed through selected ones of a plurality of openings 5 formed in the bar with which its inner end has abutting engagement. The openings 5 are spaced from each other equal distances and by selecting the proper openings a frame may be formed which has sides of the same length. The bolts have heads at their inner ends seated or countersunk in enlarged inner ends 6 of the openings 3 and at their outer ends the bolts carry winged nuts 7 which may be easily screwed upon the bolts and tightened so that the bolts will very firmly secure the bars together. The fact that winged nuts are used also allows the nuts and the bolts to be readily removed when the frame is to be taken apart and the bars moved to enlarge or reduce the size of the frame. Pins 8 are carried by the bars and project upwardly from upper faces of the bars. The pins are spaced from each other equal distances longitudinally of the bars and these pins constitute members about which a strand of yarn will be engaged as the strand is passed back and forth across the frame when the frame or loom is in use.

In order to form a frame of a greater size than permitted by the bars 1 and in addition provide the frame with portions which will serve as handles by means of which it may be conveniently held while in use there have been provided auxiliary bars 9 which may be referred to as outer sections for the main bars 1. These auxiliary bars are of the same transverse shape and dimensions as the main bars and are formed with openings 10 corresponding to the openings 5 and carry pins 11 corresponding to the pins 8. The inner and outer ends of the auxiliary bars are cut diagonally as shown at 12 and 13 in Figure 1 so that their inner ends may be disposed flat against the diagonally cut outer ends 14 of the main bars and bolts 15 passed through registering openings formed through the overlapping ends of the main bars and the auxiliary bars to securely hold the auxiliary bars in engagement with the main bars that permit removal of the same. The fact that the outer ends of the auxiliary bars are cut diagonally as well as their inner ends permits additional auxiliary bars to be applied when necessary. By comparing Figures 1 and 3 it will be seen that the ends of the auxiliary bars and outer ends 15 of the main bars may be cut diagonally in

such a direction that they extend between the inner and outer side faces of the bars at a forward incline or at a rearward incline. In either form the abutting ends of the main bars and the auxiliary bars overlap diagonally and the bolts 15 may be passed through registering openings formed through the overlapping portions and their nuts then applied and tightened to firmly hold the auxiliary bars to the main bars. The inner ends of the bars 1 may then be secured against inner side faces of the auxiliary bars and the size of the frame increased to an extent not permitted if the auxiliary bars were not provided. In addition to serving as extensions for increasing the size of the frame the auxiliary bars also serve as handles which may be conveniently grasped and the frame conveniently held while the weaving frame is in use. When the bolts are removed the main bars and the auxiliary bars may be tied in a compact bundle or placed in a box until use of the frame is again desired.

Having thus described the invention, what is claimed is:

A hand loom comprising a frame consisting of bars defining a geometrical figure and each having a rear end disposed in close-fitting abutting engagement with the inner side face of an adjoining bar, bolts passing through registering openings formed in the abutting portions of said bars and removably securing the same together in firm engagement with each other, said bars being formed with additional openings spaced from each other longitudinally thereof whereby the

bars may be shifted to adjusted positions and secured to form a frame of predetermined size, yarn-engaging pins projecting upwardly from said bars and spaced from each other longitudinally of the bars, front ends of the bars being formed with diagonally extending faces, auxiliary bars disposed longitudinally of the first bars in alignment therewith and having diagonally extending end faces conforming to the angle of the front end faces of the first bars and disposed in flat contacting and overlapping engagement therewith, bolts passing through the overlapping end portions of the first bars and the auxiliary bars, said auxiliary bars being formed with longitudinally spaced bolt-receiving openings through which the securing bolts for rear ends of the first bars are adapted to be passed and detachably secure the first bars to the auxiliary bars, and yarn-engaging pins projecting upwardly from the auxiliary bars.
